DESIGN FOR A BOTTLE

Catherine K. Gordon, Chicago, Ill.

Application January 5, 1945, Serial No. 117,268

Term of patent 14 years

(Cl. D58—6)

To all whom it may concern:

Be it known that I, Catherine K. Gordon, a citizen of the United States and a resident of Chicago, county of Cook, State of Illinois, have invented a new, original, and ornamental Design for a Bottle, of which the following is a specification, reference being had to the drawing, forming a part of the instant application, in which:

Fig. 1 is a front elevation of a bottle showing my new design;

Fig. 2 is an end view thereof; and

Fig. 3 is a plan view thereof.

I claim:

The ornamental design for a bottle, as shown.

CATHERINE K. GORDON.
